(57) **CLAIM**

The ornamental design for the protective toilet cover, as shown and described.

DESCRIPTION

FIG. 1 is a side elevation of the toilet cover of the present invention;

FIG. 2 is a plan view; and,

FIG. 3 is a front view.

The bottom view is the same as the top view and is, therefore, not shown. The invention is substantially two dimensional without contour on the top side or bottom sides and, therefore, side views are not provided. The broken line aspects of the figure depict elements that are not part of the design sought to be patented and form no part of the claimed design.

The protective toilet cover of the present invention is designed to protect the user and his clothes from contact with the toilet seat and front of the toilet pedestal. These areas are those most often in contact with the user or his clothes and prone to contamination.

1 Claim, 3 Drawing Sheets

FIG. 1

FIG. 2

FIG. 3
